CLAIM

The ornamental design for a display screen with an animated graphical user interface, as shown and described.

DESCRIPTION

FIG. 1 is a first image of a front view of a display screen with an animated graphical user interface showing our new design;

FIG. 2 is a second image thereof; and,

FIG. 3 is a third image thereof.

The dot-dash broken lines showing of a display screen in all views form no part of the claimed design. The dashed broken lines showing of the graphic elements form no part of the claimed design.

1 Claim, 2 Drawing Sheets
